UNITED STATES PATENT OFFICE.

HERMANN G. DITTBENNER, OF MINNEAPOLIS, MINNESOTA.

LIFTING-SKID FOR SAWMILL FEED MECHANISM.

No. 887,075.

Specification of Letters Patent.

Patented May 12, 1908.

Application filed August 22, 1907. Serial No. 389,678.

To all whom it may concern:

Be it known that I, HERMANN G. DITTBENNER, a citizen of the United States, residing at Minneapolis, in the county of Hennepin and State of Minnesota, have invented 5 certain new and useful Improvements in Lifting-Skids for Sawmill Feed Mechanism; and I do hereby declare the following to be a full, clear, and exact description of the invention, such as will enable others skilled in the art to which it appertains to make and use 10 the same.

My invention relates to saw mills, and has for its object to provide an improved lifting 15 skid for use in connection with saw mill feed mechanism for raising a log, cant or board from the coöperating feed rollers and moving the same laterally off from said rollers.

To the above ends the invention consists of 20 the novel devices and combinations of devices hereinafter described and defined in the claims.

The invention is illustrated in the accompanying drawings, wherein like characters 25 indicate like parts throughout the several views.

Referring to the drawings, Figure 1 is a plan view, with some parts broken away, illustrating my improved lifting skid, so-called, applied in working position with respect to a series of feed rollers. Fig. 2 is a transverse vertical section taken on the line $x^2 x^2$ of Fig. 1; and Fig. 3 is a detail in side elevation, showing the novel manner of piv- 35 otally connecting one of the skid beams to its supporting bracket.

The numeral 1 indicates feed rollers, the shafts of which are journaled in suitable bearings 2 on a supporting frame 3, and are connected by miter gears 4—5 to a common driving shaft 6, which shaft is mounted in suitable bearings 7 secured on one of the side beams of the framework 3. This shaft 6 may be driven in the usual or any suitable 40 way (not shown) and through the miter gears the several rollers 1 will be rotated in a common direction so that they are adapted to feed a log endwise.

The so-called lifting-skid is made up of a 50 pair of heavy skid bars 8, preferably in the form of castings, and having in their upper faces chain guiding grooves 9. At their right hand ends, as shown in Figs. 1 and 2, these cast skid bars 8 are bifurcated or formed with 55 downwardly curved prongs 8^a that are pivotally connected by bolts or studs 10 to the

prongs of a supporting bracket 11, which bracket is bolted or otherwise rigidly secured to the adjacent frame beam 3. These pivot bolts 10, it will be noted, are located eccentric to and outward of the driving shafts 6. This feature is important because it permits the application and removal of the skid bar without interference with the shaft, and, furthermore, makes the pivotal support entirely independent of the shaft journal. The driving shaft 6 is provided with a pair of driving sprockets 12 that are located one between the prongs 8^a of each of the skid bars 8. At their free ends, the skid bars 8 are also bifurcated to afford clearance for idle sprockets 13 which are journaled to the prongs thereof by short shafts or pins 14. Heavy sprocket chains 15 run over the alined sprockets 12 and 13 and their upper or working portions 75 run within the grooves 9 of the skid bars 8, but project above the skid bars, so that they are operative to support and carry a log or cant laterally when the skid bars 8 are raised above the upper surface of the rollers 1. 80

Mounted in suitable bearings 16 secured to the adjacent frame beam 3 below the rollers 1 and below the free ends of the skid bars 8, is a rock shaft 17 which is provided with a pair of relatively short arms 18 connected 85 by links 19 to the skid bars 8 near the free ends of the latter. The rock shaft 17 is also provided with an arm 20 which is connected by a link 21 to the piston stem 22 of a reciprocating engine, the cylinder 23 of which is rigidly supported by a suitable framework or other means (not shown). This reciprocating engine is adapted to be operated in the usual way and, as shown, the stem 24 of its distribution valve is yieldingly pressed 95 upward by a spring 25 and is provided with an operating rod 26 that usually extends above the floor of the structure in which the apparatus is installed, and is provided with a foot piece, not shown, which when stepped 100 upon forces the distribution valve against the tension of the spring 25 into its other extreme position. The arrangement should be such that when the spring 25 is permitted to operate, the distribution valve of the 105 engine will be held in a position to cause the piston of the engine, and hence the skid bars 8, to be held in their lowered positions. The lowered position of the skid bars 8 (see Fig. 2) is the normal or inoperative position of the 110 so-called lifting skid.

When the valve stem 24 is forced down-

ward, the piston of the engine will be forced upward in the usual way and through the connections described the skid bars 8 will be raised above the upper surface of the rollers 1, and the upper portions of their chains 15 will then be rendered operative to lift the log or cant from the feed rollers and feed the same laterally off from said rollers.

Hitherto it has been customary to pivot 10 the skid bars either on the driving shaft 6 or on bearings concentric therewith. This construction is objectionable because it throws the weight of the load on the shaft journals, thereby straining the same and frequently 15 throwing the same out of true alinement and, furthermore, because it makes the application and removal of the skid bars from their pivotal supports a difficult matter. As is evident, these objectionable features are 20 overcome in my present invention by providing pivotal supports for the skid bars that are independent of the shaft and its journals and are located eccentric thereto.

What I claim is:

25 1. In a mechanism of the kind described, the combination with feed rollers adapted to feed a log or cant endwise, of a driving shaft extending transversely of said feed rollers and geared to the shafts thereof, of a lifting 30 skid comprising skid bars extending transversely of said driving shaft and pivotally supported at one end by bearings that are located eccentric to and are independent of

said driving shaft and its journals, driving 35 sprockets carried by said driving shaft and alined with the pivoted ends of said skid bars, idle sprockets at the free ends of said skid bars, sprocket chains running over said skid bars and the alined sprockets, and means for raising and lowering the free ends 40 of said skid bars, substantially as described.

2. In a mechanism of the kind described, the combination with feed rollers adapted to feed a log or cant endwise, of a driving shaft extending transversely of said rollers and 45 geared to the shafts thereof, drivingsprockets on said driving shaft, fixed bifurcated bearing brackets having prongs embracing the outer portions of said sprockets, skid bars having bifurcated ends embracing the said 50 sprockets and pivotally attached to the prongs of said bearing bracket at points eccentric to and outward of said driving shaft, idle sprockets journaled in the free 55 ends of said skid bars, chains running over said skid bars and over the alined sprockets, and means for raising and lowering the free ends of said skid bars, to render the chains thereof operative, substantially as described.

In testimony whereof I affix my signature 60 in presence of two witnesses.

HERMANN G. DITTBENNER.
